27 Claims. (Cl. 20—4)

My invention relates to skeleton structures for buildings and the like, and it is an object of this invention to improve such skeleton structures with a view to enhancing their mechanical and functional qualities and to simplifying their production.

More particularly, my invention covers novel methods and means for arranging insulating cells with air spaces in the horizontal and vertical areas between the horizontal beams and vertical columns comprising the skeleton framework of the building. These sections of the frameworks of buildings, especially the vertical areas between adjacent beams and columns, are sometimes referred to as bays.

A further object of this invention resides in certain features for supporting said insulating means; so, for instance, insulating webs or strips may be braced and stiffened by elements which will at the same time brace the entire building-structure, including the ceilings or intermediate walls. It will be understood that the skeleton structures within the meaning of this invention may be buildings of any dimensions, even those where rigid, self-supporting plates are used instead of columns, stems or joists.

It is a still further object of this invention to produce the insulating cells of said wall or ceiling areas or bays from insulating webs which consist of corrugated cardboard, and to fasten and secure these webs by struts or bars pressing the angularly bent or folded edges of the insulating webs by clamping action against the posts, frames or sills of the structure. In this system, the insulating webs envelop together with other coatings each skeleton frame like boundary walls and are mutually supported by means of a series of said struts arranged like a grate between adjacent webs.

The insulating webs for vertical and horizontal walls may be provided with supporting or strengthening projections, ribs, folds and the like which can be produced by bending the web edges. In a further embodiment of this invention, the insulating webs which consist of one or more layers of plain or corrugated cardboard may further comprise coatings, such as paints or even metal foils fastened within the supporting ribs. By such coatings and coverings the qualities of the skeleton wall with respect to radiation and heat-conductivity will be improved.

The invention further resides in providing for horizontal walls, ceilings for example, a shored and subdivided vaulted or arched floor and ceiling construction enclosing insulating cells. This

vaulted or arched insulating construction may be attached by struts to the beams or joists and can be completed by a continuously extending covering or ceiling layer. The covering layer itself will preferably be supported by bars fastened on the beams and may comprise additional insulating cells.

In accordance with this invention, insulating air cells may also be produced within intermediate walls or exterior sheathings of skeleton structures by using for these walls a mixture of mortar, plaster or another cement and of light, plaited, shredded scraps consisting of cardboard, paper or other light materials. A wall or plastering layer produced in this manner may be improved, as to the insulating effect, by superimposed insulating webs.

In order to stiffen and brace the wall-core or also the outer plastering layer, diagonal wires or iron rods may be provided which are tensioned by intertwining. Such bracing elements are adapted to join adjacent or superimposed wall areas or bays of building frameworks and can at the same time be used to carry the plastering as well as to strengthen the whole building. To this end, the diagonal wires are arranged in accordance with the ground plan of the house and the position of the walls to be built up in any number above, beneath or on both sides of a beam-layer. They are rigidly connected to all skeleton parts which they cross. Since the bracing elements are embedded into a plastering layer, they do not need any considerable space and can, for this reason, also be combined with the usual wall- or ceiling-coverings. If the plastering has hardened, the diagonal wires will represent a rigid system extending over the entire house.

In order to permit the novel braced insulating elements to be separately and independently constructed, the insulating webs are preferably arranged outside or inside a layer of quickly hardening cements, such as plaster, which at the same time enclose reinforcing means, as, for instance, woven wire netting or expanded metal. The insulating webs which can also consist of separate insulating bodies each comprising a plurality of corrugated cardboard layers, form together with the cement a compact, self-supporting building element whose edges will be strengthened by frames of iron rods or wires.

As particularly suitable for the purposes of illustration, a structure has been shown which comprises a plain paper strip provided on both sides with corrugated cardboard. The heads of both corrugations are arranged in the same ver-

tical plane, so that at any point an air layer is obtained.

When combining the elements of the insulating webs, an insecticide may be added to the glue or paste; for example, arsenic can be mixed with silicious varnish. The poisonous layer is then covered by the outer paper-coating and, thus, will not endanger domestic animals.

Other objects and aims of the invention more or less specific than those referred to above, will be in part obvious and in part pointed out in the course of the following description of the elements, combinations, arrangements of parts and applications of principles, constituting the invention; and the scope of protection contemplated will be indicated in the appended claims.

In the accompanying drawings wherein I have illustrated some preferred embodiments of my invention,

20 Fig. 1 shows the filling of spaces within the framework of a building with a series of insulating webs of corrugated cardboard which webs form together vertical air cells,

25 Fig. 2 illustrates a section of an external wall with bracing elements adapted to support at the same time insulating cells (not shown),

30 Fig. 3 is a vertical section through a skeleton wall area or bay comprising insulating means and an internal and external plastering or covering,

35 Figs. 4, 5 and 7-10 are views in cross-section illustrating the structure and the arrangement of insulating webs provided with supporting ribs or folds, Fig. 5 being a view in horizontal section taken at right angles to Fig. 4 near the center thereof between the members 40.

Fig. 6 is a fragmentary perspective view of one of such webs,

40 Fig. 11 is a view in perspective illustrating an example of the formation of said supporting ribs, while

Fig. 12 shows the winding up of the novel insulating webs for transportation purposes,

45 Figs. 13-15 illustrate different forms of corrugated cardboard used as insulating webs,

50 Fig. 16 shows a supporting arch enclosing air cells, particularly for use in ceiling constructions, and

Figs. 17 and 18 illustrate in a vertical section the combination of said supporting arch structure with a continuously extending covering or ceiling layer,

55 Figs. 19 and 20 are vertical sections through a vertical wall where the wall core or a portion of the outer covering respectively is provided with plaited, shredded scraps or chips of relatively small size serving as an insulating means, Fig. 19 showing a wall in process of construction, the right hand side not yet having been plastered, and Fig. 20 showing at the same time air cells made of insulating webs and bracing elements,

60 Fig. 21 shows diagrammatically in a horizontal section a skeleton structure with four corner posts, a layer of cells and joists being braced to form a rigid frame or plate,

65 Fig. 22 shows in elevation, with certain laminations broken away similar bracing means for a vertical wall, where the plaster coatings are partly removed, while

70 Fig. 23 is a cross-section of the wall shown in Fig. 22,

Fig. 24 shows a modified structure of a horizontal wall such as floor and ceiling.

75 Fig. 25 illustrates a further form of corrugated cardboard,

Figs. 26, 28 and 29 show insulating webs in combination with wire webs or expanded metal and the application of such a structure to the manufacture of separate, self-supporting insulating plates; Fig. 27 being a perspective view of a similar structure; and

Fig. 30 is a horizontal section through the corner of a steel-skeleton structure.

Referring now to the drawings and more particularly to Figs. 1, 2 and 3, insulating dead air cells 45, 46, 47 are arranged between horizontal beams 40 and vertical columns 41 respectively; these intersecting beams and columns outlining rectangular spaces or bays and comprising the skeleton structure of the building. The cells 15 are produced by means of corrugated cardboard webs 48 having folded or bent flanges 59 which are secured in place by being urged outwardly against the supporting structure by means of bendable struts 16 in 20 any desired position. Preferably, the struts 16 have the same width as the flanges or edges 59; if, therefore, struts 16 are arranged behind each other through all air cells (Fig. 1), they brace at the same time also the panels formed 25 by the webs transversely of the bays.

Furthermore, the struts 16 may engage at each end with a wave of the corrugated material so as to avoid any damage to the latter. They may consist of wood, metal or other suitable materials, and are arched or bowed either upwards or downwards, or merely arranged in an inclined direction like the bar 17 in the remote cell of the panel shown in Fig. 1. If desired, the pressure caused by the struts 16 could be uniformly 35 divided over the angular flanges or edges of the insulating webs by means of flat bars 18 which may be provided with notches 19 for the ends of the struts 16.

40 Figs. 3 and 4 show the bays of a skeleton structure or framework provided with panels defining dead air cells and covered with plastering layers 42, the structure in Figure 3 employing the panel spacing and securing means including the elements 16 as shown in Figure 1, and the structure 45 in Figure 4 using the expedient of bending the panels as further illustrated in varying forms in Figures 6 to 15, inclusive. Fig. 5 is a horizontal section through a similar structure provided with insulating cells. Within the plastering layers, 50 diagonal bracing elements 43 are arranged which may be intertwined as indicated at 4, in Fig. 2.

55 The insulating cells 45, 46, 47 produced by insulating webs 48 may be with advantage subdivided horizontally at equal distances by supporting folds or ribs 51, as shown in Figs. 4 and 6-10. Instead of having the longitudinal edges of the webs 48 bear against the vertical columns, (Fig. 5), and in order to cover the skeleton elements and to secure the insulating cells in position, one or more intermediate layers 52 are inserted.

60 The supporting ribs 51 are more clearly illustrated in Fig. 6. They may be merely folded or also basted or stitched at the bottom as may be 65 deemed favourable in each case. In Fig. 7 which is a vertical section through insulating webs, the folds 51 of the webs 48 are arranged behind each other. Every fold is closed in this embodiment by a metal clamp 53 which may replace stitching. 70 The head of each rib 51 engages here the fold of the adjacent web so that the folds 51 support each other, while the clamps 53 are limiting this engagement.

75 In Fig. 8, two insulating webs 48 are spaced 75

from each other, their supporting ribs or folds 51 being directed outwardly from the center of the wall, while their distance may be maintained by means of clamping and spacing bars 54 or other similar spacing members. Likewise, Figs. 9 and 10 show the use of two cardboard members 48; in Fig. 9 the supporting folds 51 are turned towards each other; in Fig. 10, one of the insulating members provides supporting ribs, while the other one is plain.

Throughout all figures, 58 designates a coating which, consisting of a foil or the like, may be provided as a protection against moisture, radiation of heat, transmission of light, destruction by insects and the like. Preferably, the coating 58 is arranged at the open side of the folds 51; its margins may in this way be deflected into the folds or ribs, thus being reliably secured. If, however, the coating extends over the total height and width of the insulating boards, it may completely fill the folds 51 and be fixed by the clamps or clips 53, as shown in Fig. 7.

The coating 58 which could also be replaced by a metal paint or the like may be useful for different purposes. So, for example, the coating or paint of insulating layers, if applied to the outside of make-shift buildings, refuges against airplane attacks, or shelters for tropical countries and so on, can be done in variegated and irregular patterns, as camouflage, while the material may be impregnated at the same time against destruction by insects or the like.

If, for instance, the coating 58 consists of a metal foil, air-tightness and good protection against moisture is obtained, although the heat-conducting power of the metal is unfavourable so that the good insulating properties of the dead air enclosed within the cells will be injured. If, however, according to Fig. 4, a coating 58 of aluminum foil and an air layer is followed by another member made of corrugated cardboard, the heat conductivity of the metal foil which is at the same time stiffened by the insulating web, will be diminished. Also the radiation is decreased since the metal covering does not receive any radiation of the adjacent cardboard. On the other hand the insulating effect regarding heat and sound is enhanced by avoiding the convection by means of the horizontal supporting ribs 51. Besides, also the irregular wall surface of the corrugated paper-layers 48 impedes the convection currents within the air cells so that the air exchange of every cell is likewise reduced to the smallest degree. The optimum effect will be obtained if the distance of the air cells be about 5 cm. Last but not least, this insulating action is also assisted by the air cells enclosed within the waves of the laminated corrugated paper itself.

Fig. 11 illustrates the embodiment of supporting folds 51 in combination with the deflected edges 59 of the insulating webs 48. The edge 59 is at corresponding points provided with notches so that flaps 60 are formed. These flaps 60 are shifted to one side or the other of the edges 59 which are likewise bent over, see Fig. 11. At points 61, both parts are joined together by fastening, pasting, riveting or in any other suitable manner. In this way not only the ribs 51 are rigidly constructed, but also the whole web is stiffened. The notches provided for producing flaps 60 may already be prepared as a standard feature in the paper-plant.

Fig. 13 shows a corrugated metal foil or a corrugated impregnated cardboard web which is, on

one side, covered by a flat layer; if desired a flat web may also be arranged on the other side, as indicated at 49'. The insulating layer shown in Fig. 14 provides a flat central web covered by two corrugated strips, while Fig. 15 discloses a corrugated web where the supporting rib 51 is not reinforced, but the corrugated part is stiffened by a superposed coating such as a metal foil.

The insulating web shown in Fig. 25 in cross-section consists of a plain or flat central layer 62. The depressions 63 of the corrugated member provided on the one side of the layer 62 are situated above the depressions 64 of the corrugated member on the other side thereof, so that there is no point where paper layers only are situated directly above each other; air cells are rather formed at all places between the corrugations. In this way a particularly favourable insulation is obtained.

According to this invention, the materials used for insulating layers like those of Figs. 13-15, for instance, may be arbitrarily interchanged in correspondence with the prevailing purposes. As a pasting means for joining flat and corrugated parts, especially for tropical purposes, silicious varnish which is mixed with a certain quantity of a poison, may be used, such as arsenic. Thus, in a construction like in Fig. 14, for instance, the glue and poison will be situated inside the paper layers; the poison will therefore not harm domestic animals whilst noxious animals or insects if they destroy the outer paper layer will be affected by the poison.

The walls produced in accordance with the invention are very easy to construct; the building materials may be assembled at the building site by an inexpert staff; the insulating plates, especially if stiffened per se (Fig. 11) may be applied without further implements and can be adapted, as to size and depth, in any number to the bays 40 of the framework of the building. A considerable interchange of materials is possible. The application thereof may be arbitrary; for example, stiffened layers, as shown in Fig. 11, may be provided with a coating 58, as in Fig. 15 for example, can be sufficient as an awning against the sun, as a screening means or the like.

Figs. 16-18 show a method of shoring arches which is particularly adapted for producing ceilings. For this purpose, insulating layers are used which are of different width. In Figure 18 these insulating layers are all designated by the reference numeral 48 and are bowed to different degrees, forming air spaces 76 and 77 therebetween. Above the outermost bowed layer 55 there may be provided a moisture-proof layer 75 made of tar paper or the like, and this in turn may be covered by another layer of insulating web such as the laminated corrugated board structure 48³.

In the embodiment shown in Figs. 16 and 17, seven insulating cells 66, 67, 68, 69, 70, 71 and 72 are formed in the arch. The insulating strips 48 form the lowermost element of the arch construction in this embodiment, and the uppermost 65 arcuate element is designated 48'. Between these elements there are provided intervening insulating webs, designated 48², which are once or several times bent or broken and joined by clamps 65 so that they stiffen each other. In 70 this way, edges 73, 74 support the outer, completely arcuate layer 48' which is entirely coated by an insulating cover 75 of tar-board or similar moisture-proof material, as in Figure 18. The final covering of this structure is again 75

formed by an insulating layer 48³ which is not perforated by attachment means 65 so as to avoid the penetration of moisture into the other vault-shorings as already described.

- 5 The vault-shoring or arched construction with its insulating cells 66—72 is at once proportioned in accordance with the distance of the beams or joists, while their length, owing to the use of paper strips or webs may be of any size. The 10 edges 59 which are bent over may be fastened by bars 18 according to Fig. 17 and are clamped by means of struts 16' between the beams, so that between these struts, too, insulating cells are formed.
- 15 Directly upon the insulating web 48³ (Figs. 17 and 18) which is advantageously corrugated at the top, a ceiling layer 78 is arranged. This layer is made of quickly hardening materials and provides strengthening means 79, 80 such as expanded metal, wire fabric or the like. The plates of expanded metal which are arranged parallel with the beams 81 may provide rolled edges in order to strengthen the margins and edges of the plaster layer.
- 20 In Fig. 18, the edges of the expanded metal strips are bent upwards and downwards respectively so as to overlap each other. Since the arrangement of the elements is chosen in accordance with the actual conditions, Figs. 17 and 18 25 show several possible embodiments of the reinforcements. The core of the covering or ceiling layer 78 is formed by a packing 85 which preferably consists of wood shavings impregnated with cement. These wood shavings permit the maintenance of the cavities or cells and to internally support at the same time the layer 78. Inside the packing 85 further insulating cells 86 formed by tubes or other hollow casings of corrugated cardboard are shown.
- 30 The layer 78 which is separated from the beams or girders 81 by insulating linings 87 of corrugated material or the like, is maintained in position by strips of iron or the like 88; the latter may rigidly be connected to the beams 81 35 or may also lie with their bottom edges upon the vault-shoring (Fig. 18). If the strips 88 be attached to the beams, they have at the same time a stiffening effect. The covering layer 78 is disposed closely against the strips 88. A possible shrinkage on hardening or an expansion does not damage the covering layer, because the latter can give way upon the inclined boundary surfaces of the strips 88 during the hardening process. The size of layer 78, strengthening 40 means 79, 80 and packing 85 is chosen in accordance with the load of the ceiling. Also, for example, continuous ceiling layers 78 without a packing 85 and insulating cells 86 respectively may be provided in the vicinity of doors, stairs 45 and so on.

Between the beams a supporting strip 90 may be provided which will be attached to the floor in any suitable manner with a view to avoiding sagging due to compression of the layer of insulation board.

If building up a ceiling, for instance, first a supporting arch consisting of insulating webs 48, 48² and 75 respectively is inserted between the beams or girders, which arch may be prefabricated or manufactured outside the building ground. However, the combination of the individual insulating webs (superimposed to each other before) may be effected on the building site, if desired; the supporting arches will then only have to be cut in lengths corresponding with

the length of the beams. After that, the arches are positioned, secured by bars 18 and clamped by struts 16'. If desired, the bars 18 may be dispensed with, and the struts 16' may contact directly with the bent edges 59.

As a further step, a relatively thin layer 78' of the plaster which is to comprise the structure 78 is put upon the uppermost insulating strip 48³ which is applied over the layer 78 as already described. This layer acts instantly as an additional stiffening means, particularly since the plaster hardens very quickly. Besides, excessive moisture is avoided by adding the plaster in thin layers.

The structure of the covering or ceiling layer 15 is adapted to the prevailing conditions. So, a layer 80 of expanded metal for reinforcement or a layer 81 for separating the plastic material from the beams 81 respectively could be applied, for instance, before positioning the first covering 20 layer. If the whole covering layer 78 enclosing the packing 85 be placed between the beams, it forms together with the shoring a conjoined, continuously extending floor arch. By means of the strips 88, the individual floors are connected 25 with the beams (which may also consist of box-like sheet-iron profiles, slender or the like) and by means of the strips 87, over the beams and adjacent supporting strips 88, with the next floor 30 arch. This results, in a kind of arch construction which is the equivalent of a statically rigid plate. At places where inside the supporting arch the insulating cells 66, 68 and 71 are superimposed, the covering or ceiling layer 78 or the packing 85 respectively may be made thinner, so 35 that here the main insulating effect will be due to the supporting arch. Towards the margin parts of the arch, however, the insulating cells 69 and 72 or 70, 67 respectively are supplemented by insulating cells 86 and by the thicker structure of 40 the covering layer 78. In this way, a uniform insulation is obtained throughout the entire floor.

The building materials of the ceiling as constructed in accordance with this invention, are inexpensive, of extraordinary adaptability and 45 small weight, although of sufficient strength to comply with all requirements.

The underside of the ceiling may provide one or two insulating webs 48 and a layer of expanded metal 91 which is attached to the struts 16² by means of nails 92 and serves for carrying 50 the plastering.

Figs. 19 and 21 show the arrangement of bracing elements 3, such as wires or iron rods, for strengthening the wall sections, while the insulating cells and insulating webs respectively are stiffened and secured by diagonal elements 43 as already shown in Fig. 2. In Figure 2, the bracing wires 43 are wound round projecting nails or bolts 8, which join at the same time the framing 60 members 40, 41, and are intertwined at 4. Practically, the individual wires 43 extend in a zigzag line over large walls. So, also the diagonal bracing system of Figs. 19 and 21, comprising the wires 3 and also the outer wires 43 corresponding 65 to the similarly designated wires in Figure 2 and other figures, extends over large framing structures. The framework of Fig. 21, for instance, consisting of columns or posts 41 and beams 40, is braced by wires 3 which embrace the corner 70 posts so that the diagrammatically illustrated beam-grate becomes statically a rigid frame or plate prevented from distortion and angular displacement. Such bracing systems are peculiarly applicable to smaller buildings wherein the di- 75

agonals may cross each other; thus, a vertical (Fig. 19) or a horizontal (Fig. 21) network will be produced. The wires may be attached to the skeleton elements at all crossing points, as by the 5 nails, staples, or other suitable attachment means 5, which can also be used for securing the diagonal bracing elements 43, particularly when these elements serve for strengthening the walls or plastering as in Figs. 20, 22, and 23. In this way, 10 bracing nets will be produced in the horizontal and vertical planes of the skeleton structure.

Fig. 19 shows in cross-section a vertical separating wall where the diagonal wires 3 with their intertwined parts 4 are embedded into a mortar layer 93 which completely encloses and envelopes 15 uniformly divided thread-like scraps or chips 94 of little mass consisting of cardboard or paper. On both sides of such a uniform layer 93, 94, insulating webs 48 are arranged over each other 20 in a suitable number of layers.

Passing through the insulating layers 48 and the wall-cores 93, 94, nails, bolts or other attaching means 95 are provided to form fastening points for the diagonal intertwined wires 43.

25 Such strengthening means secure at the same time the insulating webs 48 and may finally be covered by wire or partition reinforcing webs such as lath or expanded metal. The outside is covered in known manner by a plastering layer 42.

A separating wall or partition disposed between the upper and lower beams 96 and 97 as shown in Figure 19 may be advantageously erected in the following manner. First, one of 35 the insulating strips 48 is tensioned over a temporary panel which is erected in the space between the beams. Then the wires 3 are stressed by twisting them as at 4 after which the mortar layer 93, which may include the shreds or scraps 40 94, is poured. The nails 95 can be driven into the partition as soon as the core of mortar has sufficiently hardened, the points of the nails being bent for the retention of the bracing wires 43 which are later applied and tensioned. The additional insulating layers 48 are then applied to 45 the mortar surface and an outer plastering layer 42 is applied, as shown at the left hand side of the partition in Figure 19.

It will be noted that, after the hardening, 50 cavities and holes will be formed within the cores 93, 94 at places where the scraps 94 are situated. Their insulating effect may be enhanced if the scraps are worked in a moist, swelled condition. Even if the scraps or shreds 94 are not previously 55 moistened, they will absorb moisture from the mortar and form, when dried and shrunken in place air cells and spaces which act as heat-insulating means. At the same time, the thread-like scraps 94 make the mortar smoother; they may 60 consist of chips and shavings of paper, preferably shredded corrugated cardboard.

Fig. 20 shows a wall with insulating cells 45, 46, 47 built up of sections of the insulating web or sheeting 48 and with an outer plastering layer 65 composed of scraps 94 and mortar 93 just as illustrated in Fig. 19. Similar insulating webs 48 applied to the right hand side of the wall in Figure 20, and similar to those applied in the corresponding portion of Figure 3, are covered 70 with a layer of wire screening 49 or expanded metal to form an external covering of the assembly. An outer layer of plaster 42 may then be applied. Thus, the wall appearing in Fig. 20 provides a double insulation consisting of the air 75 cells 45-47 and of the insulating layer 93, 94.

The superimposed insulating webs 48 act as a buffering layer.

Fig. 22 shows a further bracing system for a vertical wall. In this case, wires 43 are continuously tensioned in a zigzag line between the 5 beams 6, 7, where they pass over fastening means 5, such as clamps, hooks or the like. The tension of these wires is effected by intertwinnings as at 4 in Figure 21 and others.

In the case of Fig. 22 the insulating layers for 10 the vertical wall consist of corrugated cardboard webs 48 which are arbitrarily superimposed in such a way that each web overlaps the separating joints of underlying webs.

15 The outside coating of the insulating webs 48 is made in the same way as in Fig. 20, and also a series of plastering layers 42 and preferably a concrete- or cement intermediate layer 21 may be used.

20 The application of bracing diagonals 3 and insulating webs 48 in the case of horizontal separating layers may be effected, as shown in Fig. 24, in such a way that directly upon the beam 40 a layer 21 of concrete or mortar provided with 25 strengthening means 98, such as expanded metal, is arranged. The diagonal bracing system 3 is then disposed within the layer 21 above the beams 40; floor boards 25 may be arranged on a supporting bar 24 which protects portions of the 30 insulating system against compression.

24 The ceiling panel such as is shown in Figure 24 may be so arranged that the reinforced plastering or concrete layer 98, 21 is located entirely above the plane of the upper surface of the beam 40. The wires 3 are stretched across the beams 35 and reinforcing elements 98, and the insulating webs 48 are then applied thereto. The floor coating 25 is laid in the usual way, and the concrete or plastering 21 is applied to the reinforcing means 98. If desired, of course, the flooring and 40 ceiling assembly could embody the air cells 45, 46 and 47 as shown in the wall sections illustrated in Figures 3, 4, and 20, especially if additional insulating properties are required.

45 By the method just described a stiffened and rigid plate or panel will be produced which is fire-, sound- and heat-proof and which occupies but little space. The framing parts 40 may be surrounded with insulating material and can also be made absolutely fireproof. Between the framing elements and their coatings insulating webs 44 of tar-board or other elastic material may be arranged on the inner and outer side or on one side only, as indicated in Figures 1 and 3.

50 When positioning the air cells 45, 46, 47 (Fig. 5 1), it will be advantageous to proceed so that the individual initially positioned corrugated cardboard layers 48 are first maintained by a larger number of struts 16. As soon as the first (outer) plastering layer has hardened, some of 60 said struts can then be removed from the insulating cells 47. The corresponding struts 16 of the next following insulating cell 46 will then be arranged about in the same height as the remaining struts 16 in cell 47. By such proceedings 65 the entire wall depth (Fig. 1) will be progressively stiffened and braced. By the insulating means, especially by the folded edges 59 and the webs 44, the framing parts are completely coated. The insulating means for the air cells will not be injured by any fastening means since none is used 70 for attaching the struts 16.

75 Referring now to Fig. 30 this figure shows the paneling of framework cells in the case of a steel-skeleton structure. The columns or posts

41 consist of Z- or U-iron, preferably standard shapes. Upon the legs or flanges of the steel shapes, connecting elements 26, which may be of wood, are applied. Advantageously the steel elements are protected by an insulating paint. If need be, the connecting elements 26 will be secured by correspondingly shaped clamps 2.

The steel elements and the connecting arrangement (using, for instance, bolts 8 which are 10 only diagrammatically indicated) are chosen in accordance with the principles of steel structures. Also, trimming members 27 consisting of masonry or other compositions may be provided at the corners.

15 In Fig. 30, the air cells 45, 46, 47 are supplemented at the inside by an air cell 45'. At all events, the number of air cells and their dimensions may be arbitrary. The air cells are built up in such a way that first the outer cell 47 is formed by the insulating web 48. The skeleton arrangement as shown in Figure 30 may be finished off by employing the construction shown in the other figures of the drawings.

For example, diagonal bracing elements 3 and 25 43 respectively and an impregnated insulating web 44 may finally be provided at the outside of the building as in the other embodiments. The bars 18 which are clamped in their position by struts 16 in correspondence with Fig. 1 bear on the one side against the flange of the web and press the same against the beam or column 41 and on the other side against the connecting element 26, whereby the latter is pressed upon the web of the vertical post profile 41. Then, the next succeeding air cell 46 is constructed from an insulating web 48 and bars 18. By the connecting elements 26, the outside fastening of insulating webs, wire fabric or the like will be facilitated.

The insulating plates shown in Figs. 26-29 are 40 peculiarly adapted to be prefabricated outside the building ground; they comprise a cement 93, such as plaster, insulating webs 48, wire screening partition webs 98 and wires or iron rods 99. The webs 48 are either continuously extending or may 45 also consist of separated insulating bodies, such as the crossed corrugated cardboards indicated at 100 and 100', Fig. 28. Any suitable tying or attaching means indicated diagrammatically at 65 serve for joining the insulating members 100 and 100'. The edges of the webs 98 may be bent or folded as shown at 101 in Figure 29 so that they are helpful at the same time for strengthening the edges of the plates.

While Figs. 26, 28, and 29 illustrate cross-sections of insulating plates, Fig. 27 shows a perspective view of a plate the uppermost layers of which are removed so that its interior and the position of the strengthening or bracing frame 99 is visible. Plates like those of Fig. 26 may also 55 be manufactured with a thickness of 1 cm. and have nevertheless sufficient strength for use as paneling for building constructions. They can also be used as a supplement for board partitions or as carriers for plastering, since they can easily 60 be conveyed and set in place. For carrying plaster, the arrangement of corrugated parts on the outside of the plate or web, as in Fig. 26, is particularly suitable. In producing such plates, a layer of plaster is preferably brought upon a suitably dimensioned web or strip of corrugated cardboard, whereupon wire bracings 98, strengthening members 99 etc. are applied in a predetermined sequence, with an intermediate layer of cement. The corrugated shape and, thus, the insulating 75 effect of the air cells in the insulating layers will

be wholly maintained after the hardening of the cement, especially if, as commonly is done, corrugated cardboard pasted with silicious varnish be applied thereto. The stiffness of the corrugations will not even be injured during the construction of the panels.

If desired, packings or coatings of jute may be used, although the immediate contact between plaster and cardboard results in a completely rigid combination so that the individual building- 10 elements can be produced at any place.

If the plates shown in Figs. 26-29 and which comprise air cells have not yet hardened, they may be easily shaped at will. So, for instance, curved plates, angular edge plates etc. may be 15 manufactured. All these building elements can be produced outside the building ground. At the same time, the novel plates represent a favorable supplement for the manufacture of ceilings or for the bracing and support of any kind of insulating arrangements. Besides, they may be nailed upon a layer of expanded metal or be used for covering a layer of beams or other building elements. The reinforcing elements 98, 99 prevent the breaking of the plates.

I claim as my invention:

1. In a building wall or ceiling structure or the like, the combination of intersecting structural members defining substantially rectangular bays, diagonally disposed bracing tension members for 30 rigidifying said bays, said members being secured at intervals to said structural elements, and to each other where they intersect, insulating panels disposed across said bays and secured to said structural members.

2. In a building wall or ceiling structure or the like, the combination of intersecting structural members defining substantially rectangular bays diagonally disposed bracing tension members for 40 rigidifying said bays disposed on both sides of the plane of said structural members, said bracing members extending across a plurality of said bays, being secured at intervals to said wall or ceiling structure, and intertwined with each other where they intersect, insulating panels disposed 45 across said bays and secured to said structural members and additionally retained by means of said bracing members.

3. In a building wall or ceiling construction or the like as set forth in claim 1, a coating of plastic covering material on one side of said wall, said bracing members being embedded in said plastic covering.

4. A building wall or ceiling construction or the like as set forth in claim 1 in which said insulating panels comprise spaced parallel laminations of corrugated cardboard forming dead air cells within said panels.

5. A building wall or ceiling construction or the like as set forth in claim 1 in which said insulating panels comprise spaced parallel laminations of corrugated cardboard forming dead air cells within said panels and in which an additional lamination of corrugated cardboard is embedded in said plastic covering.

6. A building wall or ceiling construction or the like as set forth in claim 1 in which said insulating panel includes webs of insulating material and a layer of mortar containing shreds of fibrous material, such as wood shavings, paper 70 or cardboard scraps or the like.

7. A building wall or ceiling construction or the like as set forth in claim 1 in which said insulating panel includes webs of insulating material and a layer of plastic material containing 75

shreds of fibrous material, such as wood shavings, paper or cardboard scraps or the like, said shreds being surrounded by voids in said plastic material.

5. 8. In a building wall or ceiling construction or the like as set forth in claim 1, a coating of plastic covering material on one side of said wall, said bracing members being embedded in said plastic covering, and nails passing transversely through 10 said wall or like structure to which are secured said bracing members.

15. 9. A building partition construction adapted for wall, floor, or ceiling construction or the like, comprising spaced structural supporting members, diagonal, intersecting tension bracing members disposed across the space between said members, a panel extending across said space and comprising laminations of corrugated fibrous material, the corrugations of adjacent laminations being crossed, a layer of mortar applied to 20 said fibrous material, said tension members being embedded in said mortar layer, additional metallic reinforcements embedded in the mortar, and a final layer of plaster on said panel.

25. 10. In a building wall or ceiling structure or the like, the combination of intersecting structural members defining substantially rectangular bays, diagonally disposed bracing tension members for rigidifying said bays, said members being secured at intervals to said structural elements, and to each other where they intersect, insulating panels disposed across said bays and secured to said structural members, said insulating panels comprising a series of parallel webs of 30 insulating material spaced transversely of said panel to form dead air cells therein, each of said webs provided with flanges which are adapted to maintain the spacing between said webs, and means for wedging said flanges tightly against 35 said structural members to retain said webs in place.

40. 11. A building partition construction adapted for inner or outer walls, floors, ceilings or the like which comprises, in combination, a pair of spaced structural members, such as beams, columns, girders or the like, and an insulating panel comprising a series of parallel webs disposed in spaced relation transversely of the panel and each provided with edge flanges arranged in contact with 45 said members, and struts disposed so as to extend between the flanges on opposite edges of said webs and clamp them against said members.

45. 12. A building partition construction adapted for inner or outer walls, floors, ceilings or the like which comprises, in combination, a pair of spaced structural members, such as beams, columns, girders or the like, and an insulating panel extending between said members, said panel comprising a series of parallel webs disposed in spaced 50 relation transversely of the panel and each provided with edge flanges arranged in contact with said members, and resilient wedging strips sprung into position between the flanges on opposite 55 edges of said webs to clamp them against said members.

60. 13. A building partition construction adapted for inner or outer walls, floors, ceilings or the like which comprises, in combination, a pair of spaced structural members, such as beams, columns, girders or the like, and an insulating panel extending between said members, said panel comprising a series of parallel webs disposed in spaced 65 relation transversely of the panel and each provided with edge flanges arranged in contact with 70

said members, and flat resilient wedging strips sprung into position between the flanges on opposite edges of said webs to clamp them against said members, said strips being of substantially the same width as said edge flanges and the 5 spaces between said webs, so as to provide stops therebetween.

14. A building partition construction adapted for inner or outer walls, floors, ceilings or the like which comprises, in combination, a pair of spaced structural members, such as beams, columns, girders or the like and an insulating panel extending between said members, said panel comprising a series of insulating webs spaced transversely of said panel, each secured along its edges 15 to the adjacent structural members and adapted to provide insulating cells, each of said webs also being provided at intervals with folds adapted to project transversely of said panel toward the adjacent web in order to subdivide the cells formed 20 between said webs.

15. The building construction as set forth in claim 14 in which said webs comprise sheets of corrugated cardboard having layers of plain paper secured thereto. 25

16. A building construction as set forth in claim 14 in which the folds of adjacent webs are directed toward each other and disposed alternately along the length of the panel.

17. A building partition construction adapted for inner or outer walls, floors, ceilings or the like which comprises, in combination, a pair of spaced structural members, such as beams, columns, girders or the like and an insulating panel extending between said members, said panel comprising a series of insulating webs spaced transversely of said panel, each secured along its edges to the adjacent structural members and adapted to provide insulating cells, each of said webs also being provided at intervals with folds adapted to 35 project transversely of said panel, the folds of adjacent webs being averaged from each other, and distancing members arranged between adjacent webs. 40

18. The building construction as set forth in claim 14 in which each of the folds are stitched along a line spaced slightly from the plane of the web, whereby a recess of limited depth is formed on the opposite side of said web for the reception of the head of a fold on an adjacent 50 web.

19. In a building construction as set forth in claim 14, the combination of additional laminations, such as metal foil or the like, to said webs, portions of said additional laminations being anchored within certain of the folds in said webs, whereby further insulating, moisture and radiation resisting, and insect repelling properties are 55 provided.

20. The building construction as set forth in claim 11 in which each of the webs is provided at intervals with folds adapted to project from the plane of said web toward the adjacent web to further subdivide the cells of the panel, the ends of said folds being slit and folded into substantially the same planes as the edge flanges of 60 said webs. 65

21. The building construction as set forth in claim 11 in which the structural members comprise flanged metal structural elements of suitable cross sectional configuration, and in which slotted members are applied to the flanges of 70 said metal elements, against which the edge flanges of said webs may be clamped at such points. 75

22. The building construction as set forth in claim 11 in which the edge flanges of said spaced webs are superposed and together clamped by said wedging strips between adjacent structural members, the body portions of certain of said webs being bowed to form an arched construction, such as for example in a floor or ceiling arrangement, and a continuously extending covering layer supported by said arched construction.
- 5 23. A building partition construction adapted for floors, ceilings or the like which comprises, in combination, a pair of spaced beams or joists and an insulating panel extending therebetween, said panel comprising a series of insulating webs of 10 different lengths arranged one above the other to provide an arched structure containing insulating cells, roof-like angles formed in certain of said webs, and means for securing said angles to adjacent webs to form a trussed construction, 15 edge flanges on all of said webs arranged in superposed relation at the sides of said panels, and wedging struts adapted to clamp said superposed flanges against said structural members.
24. A building partition construction adapted 20 for floors, ceilings or the like which comprises, in combination, a pair of spaced beams or joists, and an insulating panel extending therebetween, said panel comprising a series of insulating webs of different lengths arranged one above the other 25 to provide an arched structure containing insulating cells, the lowest web being substantially flat and disposed in a horizontal plane, the uppermost being substantially arcuate, and intermediate webs having roof-like angles formed therein, 30 means for securing said angles to adjacent webs to form a braced truss-like arched construction, means for securing the edges of said construction to said structural members, and covering means for said arch construction.
- 35 25. A building partition construction adapted for floors, ceilings or the like which comprises, in combination, a pair of spaced beams or joists and 40
- an insulating panel extending therebetween, said panel comprising a series of insulating webs of different lengths arranged one above the other to provide an arch structure containing insulating cells, and a continuous covering layer of quick 5 hardening plastic material superposed upon said arch construction.
26. A building partition construction adapted for floors, ceilings or the like which comprises, in combination, a pair of spaced beams or joists and 10 an insulating panel extending therebetween, said panel comprising a series of insulating webs of different lengths arranged one above the other to provide an arch structure containing insulating cells, a continuous covering layer of quick hardening plastic material superposed upon said arch construction, cavities formed in said plastic material, and filling material in said cavities comprising wood shavings or the like impregnated with cement mortar and adapted to form a rigid 15 body.
27. A building partition construction adapted for floors, ceilings or the like which comprises, in combination, a pair of spaced beams or joists and an insulating panel extending therebetween, 20 said panel comprising a series of insulating webs of different lengths arranged one above the other to provide an arch structure containing insulating cells, a continuous covering layer of quick hardening plastic material superposed upon said 25 arch construction, cavities formed in said plastic material, and filling material in said cavities comprising wood shavings or the like impregnated with cement mortar and adapted to form a rigid body, said plastic material being provided with reinforcing elements to take tension 30 stresses and additional supporting means for said superposed body of material, comprising strips secured to adjacent beams and received in recesses formed in said plastic body.
